FIG. 2.

UNITED STATES PATENT OFFICE.

JACOB SODERBERG, OF PITTSBURGH, PENNSYLVANIA, ASSIGNOR TO PITTSBURGH PLATE GLASS COMPANY, A CORPORATION OF PENNSYLVANIA.

GLASS-ROLLING MECHANISM.

1,398,046.

Specification of Letters Patent. Patented Nov. 22, 1921.

Application filed July 21, 1919. Serial No. 312,131.

To all whom it may concern:

Be it known that I, JACOB SODERBERG, a citizen of the United States, and a resident of Pittsburgh, in the county of Allegheny and State of Pennsylvania, have made a new and useful Invention in Glass-Rolling Mechanism, of which the following is a specification.

The invention relates to apparatus or machines for rolling glass, such as employed in the manufacture of plate glass and preparatory to supplying the sheets thus formed to the annealing leer. The invention has for its primary objects the provision of an improved rolling apparatus, wherein provision is made for maintaining the roll employed at a uniform temperature during the periods between successive rolling operations and the provision of improved and simplified means for operating the roll employed. One embodiment of the invention is illustrated in the accompanying drawings, wherein:—

Figure 1 is a plan view of the mechanism. Fig. 2 is a side elevation. Fig. 3 is a transverse section on the line III—III of Fig. 4, and Fig. 4 is a partial end elevation of the mechanism.

Aside from the improved mechanism for moving the roll back and forth longitudinally of the table, one of the most important features of the invention consists in the arrangement for maintaining the roll at a uniform temperature during the period of rest between rolling operations. In rolling mechanism as now used, the roll remains stationary at one end of the table between casting operations, and, as a result, becomes more highly heated on the side adjacent the table. As a result the unequal expansion bulges the roll on the side adjacent the table, and the sheet of glass formed by moving the roll over the table is of varying thickness, resulting from the non-uniformity of the roll. The present invention is designed to avoid this difficulty by providing for the rotating of the roll for the greater portion of the period of time between casting operations so that it is maintained of uniform temperature. The invention also contemplates the provision of means for maintaining the roll at any desired temperature while in its position of non-use between the casting operations, such means

comprising either heating or cooling means, depending upon the requirements.

In its preferred embodiment the invention includes means for automatically elevating the roll and continuing its rotation when such roll reaches its position at the end of the table, the same driving mechanism being employed for moving the roll back and forth along the table and for rotating it when it reaches the end of the table. In the embodiment of the invention illustrated, the mechanism for lifting the roll comprises a tilting cradle provided with supporting rollers which the roll engages when it reaches its end position, such engaging causing the tilting of the cradle to carry the roll away from the table, at which time the rollers of the cradle permit the continued rotation of the roll.

Referring now to the drawings, 1 is the casting table, which is of any approved type, supported upon the base members 2 and 3, and 4 is the roll, which may also be of any approved type, and is mounted to move longitudinally of the table. The table is provided adjacent its side edges with the rails 5—5 (Fig. 1), which constitute a track upon which the roll is supported, such rails also constituting a limiting means for the edges of the sheet of glass which is formed on the table. At the left hand end of the table is an apron 6 bridging the space between the table and the receiving member 7 of the leer, such apron being supported upon the brackets 8 and 9. This apron is provided at its edges with rails 10—10, for receiving the roll, and inclined upwardly, so that when the roll reaches its position at the left hand end of the table, as indicated in dotted lines in Fig. 2, it is raised above the table a distance sufficient to permit the stowing tool to move the sheet of glass which has been formed beneath the roll onto the leer receiving member 7.

The roll is journaled at each end in a triangular shaped frame 11, such frame being carried on the end of the roll as indicated in Fig. 4 and being provided with a sprocket wheel 12, keyed to the end of the roll, such sprocket wheel being operated from an endless chain 13, as hereinafter described. The frame is also provided with a pair of roll-

- ers 14 and 15 journaled freely upon axles 16-16. These axles 16-16 also carry sprocket idlers 17-17, about which the chain 13 passes, as indicated in Fig. 2. The 5 rollers 14 and 15 engage the rails 18-18 (Fig. 1), which extend longitudinally of the casting table at the sides thereof, the extremes of movement of the roll and frames 11 being indicated in dotted lines in Fig. 2.
- 10 The chain 13 in addition to passing around the sprockets on the frame 11, passes around the idler sprockets 19 and 20 at the ends of the table, and also around the driven sprocket 21. The sprocket 20 is preferably mounted 15 for adjustment longitudinally of the table for convenient tightening of the chain. The sprocket 21 is carried by a countershaft 22, and such countershaft is driven by the chain 23 passing around the sprockets 24 and 25.
- 20 An electric motor 26 is preferably employed with a reducing transmission 27 intermediate such motor and the shaft on which the sprocket 25 is mounted. It will be understood that the operating means for the roll 25 as above described are the same at each end of the roll.
- 25 The rails 18, on which the rollers 14 and 15 move, are bent up at their left hand extremities as indicated at 19^a in Fig. 2, to 30 follow the upward movement of the roll on its inclined track, such arrangement serving to keep the rollers 14 and 15 in contact with their track, so that lost motion of the frames 11 is avoided. The rails 10 and 18 35 are also provided with sharply upturned portions 28 and 29 at their extreme left hand ends, such portions practically constituting stops to prevent further movement of the roll to the left.
- 40 It will be seen from the foregoing that the operation of the sprocket chain 13 rotates the roll 4 and moves it longitudinally of the table in a direction dependent upon the direction of the movement of the chain, 45 the motor being stopped after the roll has moved to the left to the extreme position indicated in dotted lines at the left hand end of the table in Fig. 2. This movement carries the roll above the surface of the apron, 50 permitting the passage of a stowing tool to move the glass from the table to the leer. The right hand end of the table is also provided with mechanism for lifting the roll slightly away from the table and away from 55 the supporting rails 5, so that the roll may be rotated in the period of time between successive casting operations. This mechanism includes a cradle 30 at each side of the table, pivoted upon the pin 31, and each provided 60 with a pair of rollers 32 and 33. A stop 34 is provided on the supporting bracket or frame 35, so that when the cradle 30 reaches the position illustrated in Fig. 3, its further movement to the right is stopped. Another 65 stop 34^a (Fig. 3) limits the movement of

the cradle in the reverse direction. As indicated at 36 in Fig. 3, the end of the rail 5 is inclined upwardly, and terminates at such point 36, so that when the roll carried by the cradle reaches the extreme position to the right, it just clears the ends of the rails 5 and is free to rotate upon its supporting rollers 32 and 33.

The inertia of the roll and the pull of the chain 13 will ordinarily carry the roll to the position illustrated in Fig. 3, although such movement involves a slight lifting of the roll. Similarly, when the movement of the chain is reversed, the pull thereof will carry the roll to the left on to the rails 5. However, in order to insure positively these two movements, provision is made for preventing the rotation of the rollers 32 and 33 at certain periods in order to insure that the roll will pull itself to its proper positions. 85 The roller 33 is provided with a ratchet 37, adapted to be engaged by a pawl 38, carried by the cradle 30. When the cradle is in its left hand position, the pawl 38 prevents the rotation of the roller 33 in a counter clockwise direction. When the roll 4, moving to the right and turning in a clockwise direction, engages this roller, the roller is held from rotating and the roll turns to the right on the roller thus positively moving to the 95 right until such movement is stopped by the engagement of the cradle with its stop 34. At this time the end of the stop screw 38 engages the pawl, thus releasing its engagement with the ratchet 37, so that the roller 100 is free to rotate as long as the cradle occupies the position shown. Similarly, the roller 32 is provided with a ratchet and pawl 39 and 40, so that when the movement of the roll is reversed, the rotation of the roller in a clockwise direction is prevented and the roll positively moves itself to the left.

In operation glass is teemed across the table in the usual manner, the roll at that time occupying a position to the left of that indicated in Fig. 3, at which time the roll rests upon the rails 5 and acts as a stop for the mass of molten glass. After the teeming operation the motor is started so that the roll is carried from the right hand end of the table to the position indicated in dotted lines at the left hand end of the table, rolling out the sheet of glass and the roll being lifted above the glass when the left hand end of the table is reached. The motor is stopped when the roll reaches this position, and the glass is stowed by shoving it to the left beneath the roll. The motor is then reversed and the roll carried back to its position at the right hand end of the table. When it reaches this position it strikes the rollers 33 on the cradles, and these cradles swing to the right, disengaging the roll 120 from its tracks 5. The motor is still allowed 125 to run, carrying the roll to the left end of the table, where it strikes the cradles 30, which swing to the right, disengaging the roll from its tracks 5. The motor is still allowed 130

to operate so that the turning of the roll upon its supporting rollers 32 and 33 is continued. The temperature of the roll is thus maintained uniform until the next teeming 5 operation, since the face of the roll toward the table is being constantly shifted, and the uniform application of a heating or cooling medium is facilitated. In case it is desired to heat the roll, a gas pipe 41 may be employed or the roll may be heated by other suitable exterior heating means. Similarly, if it is desired to cool the roll, this may be done by a pipe corresponding to the pipe 41, through which a cooling fluid, such as air, 10 may be forced and discharged upon the roll, or by any other desired exterior cooling means, the invention not being limited to any particular means, and a uniform effect upon the roll being secured because of its 15 constant movement past the heating or cooling agent.

It will be seen that the provision of the frames 11 at the ends of the rolls, with the chains 13, serve to give the roll a positive 20 movement back and forth along the table, and that the use of the rollers 14 and 15 on such frames serves to keep the frames 11 in their proper positions at all times, the bent up portion at 19^a guarding against tilting 25 movement of the frames, and a similar means, although of much smaller size, is provided at the right hand end of the table for engaging the roller 15 when the roll is raised in the cradle, such means comprising a hump 30 member 42 secured to the top of each rail 18.

What I claim is:

1. In combination in glass rolling mechanism, a table, supporting tracks extending along the sides of the table, a roll having its 40 ends resting upon said tracks, and operating means for each end of the roll comprising a frame movable longitudinally of the table, in which the end of the roll is journaled, an operating wheel carried by the end of the 45 roll and mounted to turn therewith, a guide rail extending along the side of the table, means on the frame engaging said rail, a pair of idler wheels mounted on opposite sides of the roll, an endless flexible driving 50 member extending longitudinally of the table and around the operating wheel and the two idlers, and means for operating said flexible member.

2. In combination in glass rolling mechanism, a table, supporting tracks extending along the sides of the table, a roll having its ends resting upon said tracks, and operating means for each end of the roll comprising a frame movable longitudinally of 55 the table, in which the end of the roll is journaled, an operating wheel carried by the end of the roll and mounted to turn therewith, a guide rail extending along the side of the table, a pair of wheels on the frame 60 engaging said rail, a pair of idler wheels

mounted on opposite sides of the roll, an endless flexible driving member extending longitudinally of the table and around the operating wheel and the two idlers, and means for operating said flexible member. 70

3. In combination in glass rolling mechanism, a table, a roll, supporting tracks extending along the sides of the table on which the roll rests, means whereby the roll is moved longitudinally of the table, means for 75 moving the roll out of contact with the tracks at one end of the table, means for rotating the roll in said position at the end of the table, and temperature modifying means adjacent the exterior of the roll when 80 in said end position.

4. In combination in glass rolling mechanism, a table, a roll, supporting tracks extending along the sides of the table on which the roll rests, and is adapted to move 85 to roll the body of glass lying therebetween, power means for rotating the roll to cause it to move back and forth along the tracks depending on the direction of rotation, and means whereby the roll is removed from the tracks and rotated by said power means intermediate the rolling operations. 90

5. In combination in glass rolling mechanism, a table, a roll, supporting tracks extending along the sides of the table on which the roll rests, power means for rotating the roll to cause it to move back and forth along the table, and means for automatically removing the roll from the tracks 95 when it reaches one extreme of movement, the said power means being arranged to continue the rotation of the roll after it is lifted. 100

6. In combination in glass rolling mechanism, a table, a roll, supporting tracks extending along the sides of the table on which the roll rests, power means whereby the roll is rotated and moved longitudinally of the table, and means actuated by the movement of the roll for removing the roll from the tracks and supporting it for rotation when it reaches one extreme of movement, the said power means being arranged to continue the rotation of the roll in said 105 extreme position. 110

7. In combination in glass rolling mechanism, a table, a roll, supporting tracks extending along the sides of the table on which the roll rests, means whereby the roll 115 is moved longitudinally of the table, and a tilting cradle actuated by the movement of the roll for lifting the roll from the tracks when it reaches one extreme of movement without stopping the rotation of the roll. 120

8. In combination in glass rolling mechanism, a table, a roll, supporting tracks extending along the sides of the table on which the roll rests, and is adapted to move 125 to roll the body of glass lying therebetween, 130

means whereby the roll is moved from the tracks and rotated intermediate the rolling operations, and means for modifying the temperature of the exterior of the roll while so rotating intermediate said rolling operations.

9. In combination in glass rolling mechanism, a table, a roll, supporting tracks extending along the sides of the table on 10 which the roll rests, and is adapted to move to roll the body of glass lying therebetween, means whereby the roll is moved from the tracks and rotated intermediate the rolling operations, and means for applying heat to 15 the exterior of the roll while so rotating intermediate said rolling operations.

10. In combination in glass rolling mechanism, a table, a roll, supporting tracks extending along the sides of the table on 20 which the roll rests, means for rotating the roll to cause it to move back and forth along the table, and means for automatically lifting the roll from the tracks when it

reaches one extreme of movement, comprising a tilting cradle provided with rollers 25 for engaging the roll and supporting it for rotation.

11. In combination in glass rolling mechanism, a table, a roll, supporting tracks extending along the sides of the table on 30 which the roll rests, means for rotating the roll to cause it to move back and forth along the table, and means for automatically lifting the roll from the tracks when it reaches one extreme of movement, comprising a tilting cradle provided with rollers for 35 engaging the roll and supporting it for rotation, the said rollers being provided with automatic stop means to restrict the rotation of the rollers and facilitate the movement 40 of the cradle while it is moving from one position to another.

In testimony whereof, I have hereunto subscribed my name this 18th day of July, 1919.

JACOB SODERBERG.
